PRESS ROLL FOR PAPERMAKING

Harry G. Specht, Montclair, N. J.

Application July 13, 1942, Serial No. 450,687

8 Claims.

(Cl. 92—49)

The present invention relates to improvements in press rolls. While the principle of the invention may find application in many fields it is especially advantageous in paper machinery, and particularly in the press part of such machines, where the precise functioning of the press rolls plays an important part in the quality and form of the paper being made. For the purpose of the present description, the general term "press roll" is to be understood as applying to any of the various rolls in relation to which the paper sheet passes, included in which are dandy rolls, couch rolls, suction press rolls, felt supporting press rolls, and felt guiding and tensioning rolls. Because of the special requirements of the felt supporting press rolls, the present description and illustrations are, for the sake of convenience, directed to these, but the application of the invention in other uses will be apparent from this disclosure.

The press part of the paper machine consists of several sets of press rolls, usually three, each consisting of a bottom and a top roll between which the felt carrying the paper sheet coming off the Fourdrinier part of the paper machine is fed, the bottom roll supporting the felt and paper and the top roll exerting pressure thereon to squeeze water from the paper sheet. These rolls are supported at their ends, the bottom roll being usually supported in journal bearings fixed to the frame of the machine, while the top roll is supported at its ends in journal bearings carried upon movable arms which adjustably position the roll in predetermined spaced relation to the bottom roll, and upon which arms suitable weights or pressures are applied for the purpose of obtaining the desired pressure on the felt and paper sheet. The rolls are therefore in the nature of beams, and as any beam will deflect or bend more or less between its supports because of its own weight and because of opposite pressures applied at its ends and at its central portion, it has been necessary in order to establish a uniform spacing and pressure at the nip between the bottom and top rolls to provide their surfaces with a predetermined crown so that the downward deflection of the bottom roll and the upward deflection of the top roll will result in a parallel relation of the roll surfaces at the nip.

As numerous variables enter into the construction and operation of these rolls, the provision of the proper crowning is an extremely difficult procedure, and in order to obtain approximately perfect results various compromises and sacrifices are necessitated in such roll characteristics

as flexibility, weight, diameter, surface formation and surface coverings. For instance, the bottom roll is usually covered with rubber for the purpose of compensating for faulty crowning, or variations in deflection resulting from the application of different pressures, and also for preserving the life of the felts, but such rubber covering results in an increase in the width of contact between the rolls and a sacrifice of pressure, so that the paper sheet goes to the driers containing a larger portion of water than would be the case with a bottom roll without a rubber covering. Also, the rubber is constantly flexed as it is pressed between the rolls, resulting in a bunching of the rubber at the entrance side which impedes the removal of water, causing it to be carried into the nip of the rolls, and also resulting in a corrugated or washboard effect. Consequently, such rubber covered rolls must be 10 reconditioned after a short use. The deterioration of the rubber covering is further aggravated by the fact that a crowned roll has a greater surface speed at its larger diameter center portion than it does at its smaller diameter ends, 15 causing slippage between the roll and the felt and resulting in wear upon the felts and a tendency to non-uniformity in the paper sheet. Also the crowning of the rolls causes the roll body to deflect during each revolution and if this deflection is to take place without producing uneven pressures upon the paper sheet, the roll must have a pronounced degree of flexibility.

It is obvious, from the foregoing, that a non-deflecting cylindrical press roll without crowning will obviate the numerous disadvantages of the previously known press rolls, and will enable the rolls to be provided with any surface or structural characteristics desired for the purpose of obtaining efficient water removal, perfect paper surface and formation, and long felt life, and without compromise or sacrifice in connection with the diameters, weights, lengths and applied pressures of the rolls. It is an object of the invention to provide a non-deflecting cylindrical press roll which is capable of use in any of the various parts of the paper machine, either alone, as a top press roll, as a bottom roll, or as both top and bottom rolls. It is particularly proposed to provide such roll in the form of a rotatable 20 tubular cylinder, through which is engaged a non-rotatable supporting beam capable of deflection within the tubular cylinder, and between which beam and the cylinder there are arranged a series of pressure elements suitably spaced along the 25 length of the beam and cylinder, whereby com-

pensating variable pressure may be applied between the variable points of deflection of the beam and the constant straight cylindrical surface of the tubular cylinder. Such pressure elements may be of any desired form, but preferably consist of inter-connected hydraulic units wherein there is obtainable an infinite degree of compensation and variation between the several units, resulting in a uniform application of pressure across the length of the roll irrespective of variations in the degree of deflection of the beam. As this uniform pressure across the roll is directly proportional to the applied pressure upon the roll, it is obvious that any desired pressure may be applied at the nip between the rolls upon the paper sheet and felt and that the unit pressure per square inch will be uniform across the paper sheet, thus resulting in a uniform removal of water and a uniform surface formation and paper thickness.

With the above and other objects in view, embodiments of the invention are shown in the accompanying drawings, and these embodiments will be hereinafter more fully described with reference thereto, and the invention will be finally pointed out in the claims.

In the drawings—

Fig. 1 is a side elevation of a pair of press rolls, incorporating the invention, the right hand end being broken away.

Fig. 2 is an end elevation, showing the supporting and pressure applying lever of the top roll.

Fig. 3 is a view, partially in side elevation and partially in vertical section of the left hand end of the top press roll, incorporating the invention, and on a somewhat larger scale than the scale of Fig. 1.

Fig. 4 is a transverse vertical sectional view, taken along the line 4—4 of Fig. 3.

Fig. 5 is a perspective view of one of the pressure applying units.

Fig. 6 is a perspective view of a section of the deflecting beam, partially broken away, and showing one of the beam supported hydraulic pressure applying units for cooperation with the cylinder engaging pressure applying unit illustrated in Fig. 5.

Fig. 7 is a transverse sectional view, showing a modification of the invention in which the hydraulic pressure applying unit consists of a bellows member.

Fig. 8 is a transverse sectional view of another modified form of the invention in which the hydraulic pressure applying unit consists of a hydraulic cylinder member.

Fig. 9 is a view, partially in side elevation and partially in vertical section, of a further modified form of the invention in which the hydraulic pressure applying means consists of a continuous hydraulic hose member.

Fig. 10 is a transverse sectional view, taken along the line 10—10 of Fig. 9.

Fig. 11 is a diagrammatic side elevation of a pair of press rolls of heretofore known type, in which both the bottom and top rolls are crowned, this view showing the two rolls in spaced static relation.

Fig. 12 is a similar view of the press rolls as shown in Fig. 11 in operative relation and showing the two rolls deflected.

Fig. 13 is a diagrammatic side elevation of a pair of press rolls, in which the top press roll, in accordance with the invention, cooperates with

a crowned bottom roll, and showing the two rolls in spaced static relation.

Fig. 14 is a similar view of the press rolls as shown in Fig. 13 in operative relation with the top roll beam and the bottom roll deflected.

Fig. 15 is a diagrammatic side elevation of a pair of press rolls, in which the top roll is crowned and cooperates with a bottom roll according to the invention, and showing the two rolls in spaced static relation.

Fig. 16 is a similar view of the press rolls as shown in Fig. 15, with the top roll and the beam of the bottom roll deflected.

Fig. 17 is a diagrammatic side elevation of a pair of press rolls, in which both the top and bottom rolls incorporate the invention, and showing the two rolls in spaced static relation.

Fig. 18 is a similar view of the press rolls as shown in Fig. 17 in operative relation, and showing the beams of the top and bottom rolls deflected.

Similar reference characters indicate corresponding parts throughout the several figures of the drawings.

Referring to the drawings, and more particularly to Figs. 1 to 6 thereof, the bottom press roll 10 as shown in Figs. 1 and 2 is of heretofore known type, and is supported at its shaft ends 11 in journal bearing supports 12 mounted upon the frame 13 of the machine. This bottom roll may be of straight cylindrical form in installations where such roll may be of sufficiently large diameter and relatively short length that there is no appreciable deflection and crowning is not necessary, or it may be slightly crowned to compensate for any calculated deflection between the bearing supports 12.

The upper roll, which incorporates the invention, comprises a cylindrical tubular roll member 14 adapted to be driven by any suitable means, as for instance drive gearing engaged with the ring gear 15 shown secured in one end of the roll 14. At suitable intervals within the roll 14, there are provided track rings 16, preferably welded into place, and which are adapted to be engaged by the pressure applying units cooperating between the beam and the roll 14, as will presently more fully appear.

Extending through the roll 14 and projecting from each end is a deflection beam member, indicated generally as 17, upon each end of which there is secured, preferably by welding, an angular bracket 18 secured by bolts 19 to the supporting and pressure applying lever arm 20, pivotally mounted at 21 at each end of the frame member 13, this lever being adapted to be raised and lowered to adjust the spacing between the top and bottom rolls and to have pressure applied to its outer end for the purpose of pressing the top roll toward the bottom roll, the amount of pressure applied to the levers being distributed as substantially uniform unit pressures per square inch along the length of the roll to impart uniform pressure to the felt 22 and the paper sheet 23 engaged in the nip of the rolls. The pressure applying means for the lever may be of any suitable type, as for instance the hydraulic cylinder 24, as shown in Fig. 2, or the usual mechanical type in which power multiplying levers and weights are connected to the lever.

The beam 17 is conveniently and economically constructed from structural steel beam members of standard form, the preferred construction as illustrated consisting of an I-beam member 25 constituting a core for the beam, a pair of side

plate strip members 26-28 secured at each side of the I-beam member to the edges of its upper and lower flanges, a top plate strip member 27 secured to the upper side of the I-beam and the upper edges of the strip members 26 and projecting at each side thereof, a pair of channel-beam side members 28-28 of relatively greater depth than the I-beam member secured to the underside of the projecting longitudinal marginal portions of the top plate member 27, and secured at their lower inwardly extending flange portions to a pair of angle-beam bottom members 29-29, having their vertical flanges disposed inwardly in spaced relation to each other and projecting downwardly to provide at the base of the beam structure a longitudinally extending guide slot in which the pressure-applying cylinder-engaging units, presently to be more fully described, are engaged and guided. These angle-beam members 29-29 are braced at suitable intervals by pairs of block members 30-30 secured between them, and which with the vertical flanges of the angle-beam members constitute vertical rectangular guide passages for the pressure applying units. In vertical alignment with the vertical central planes of the rectangular guide passages for the pressure applying members there are secured upon the outer sides of the channel beam members 28-28 vertical guide and positioning blocks 31-31, for engagement with the vertical side arm portions of the cylinder-engaging pressure-applying members, as will presently more fully appear. The several parts of the beam member are conveniently secured together by welding, but it will be understood that they may be riveted or otherwise suitably secured together.

The cylinder-engaging pressure-applying units, which are provided at suitably spaced points along the length of the beam and cylinder each consists of a pair of substantially U-shaped yoke portions 32-32, the lower parts of which are preferably arcuate and concentric to the cylinder 14, and the side arm parts of which are vertical and parallel to the sides of the beam. Between the yoke portions 32-32, there are rotatably supported upon shafts 33 three rollers 34, one of these rollers being positioned centrally of the lower end of the unit and the other two being positioned at the upper ends, the three rollers adapted to engage the track member 16 of the rotatable cylinder 14, so as to provide substantially equal spaced anti-friction roller support for the cylinder. The two yoke portions 32-32 are integrally connected together by means of a pillar portion 35, of rectangular block form connected across the central lower arcuate parts of the yoke members in spaced relation to the bottom roller 34, this pillar member being suitably shaped and dimensioned to have vertical sliding movement in the guide passage of the beam member provided between the block members 30, the upper surface of the pillar portion projecting upwardly into the beam member in opposed spaced relation to the bottom flange of the I-beam member 25, which constitutes a longitudinal platform support for the series of hydraulic pressure-applying units arranged to exert pressure between the pillar portions 35 and the beam.

The hydraulic pressure-applying units may be of any suitable type, and are shown in the embodiment illustrated in Figs. 1 to 6 as consisting of a series of hydraulic diaphragm units 36 secured at their upper sides by bolts 37 to the lower flanges of the I-beam member 25, the upper flange of the I-beam member and the top plate member

27 being provided with holes 38-38 in alignment with the bolts 37 to permit access thereto by suitable wrench means. Each of the hydraulic pressure-applying diaphragm units 36 is connected by a coupling connection 39 to a pipe member 40, which is common to the several hydraulic pressure units, and extends through the longitudinal space of the beam between one side of the I-beam member 25 and one of the side plate members 26 outwardly at one end through the angular end bracket 18 where it connects with a suitable source of hydraulic fluid pressure supply.

In Fig. 7, I have illustrated a modification in which the hydraulic pressure applying unit consists of a hydraulic bellows 36a, and in Fig. 8 I have illustrated another modification in which the hydraulic pressure applying unit consists of a hydraulic cylinder ram 36b, these units being connected by means of the bolts 37 to the base flange of the I-beam in similar manner to the connection of the diaphragm unit 36 in the embodiment illustrated in Figs. 1 to 6.

In Figs. 9 and 10, I have illustrated a further modified form of the invention in which a hydraulic pressure hose 41 is extended through the roll in interposed relation between the deflection beam and the cylinder engaging pressure-applying units. In order to accommodate this hydraulic pressure hose the deflection beam is somewhat modified in structure from that employed in the other embodiments of the invention, the I-beam member 25a being relatively narrower in width and the side plates strip members 26a-26a being extended below the I-beam member into contact with the angle-beam bottom members 29a-29a, where it is secured to these members and to the inner edges of the lower flanges of the channel-beam side members 28a-28a. The top plate strip member 27a and the vertical guide and positioning blocks 31a-31a are substantially the same as in the other embodiments. This construction provides a relatively deep narrow channel in which the hose may be effectually confined.

At the underside of the I-beam member there is engaged a contact strip 42, extending the length of the beam and grooved at its underside, as at 43, to engage the upper side of the pressure hose. The underside of the hose is engaged by a series of pressure shoe members 44, each provided with a grooved upper surface 45 for engagement with the hose, one of these block members being provided in relation to each of the cylinder-engaging pressure-applying units, and their upper portions slidably contacting with each other at their extremities so as to provide a continuous grooved surface for engaging the hose. Centrally in the underside of each block member, there is provided a rectangular recess 46 corresponding in shape to and adapted to interlocking engage over the pillar portion 35 of the cylinder-engaging pressure-applying unit. The side surfaces of the pressure shoe members are parallel and their thickness is such that they have sliding engagement for vertical movement 60 between the angle-beam members 29a-29a and the side plate members 26a-26a of the deflection beam.

The operation is substantially similar to the other embodiments of the invention, the hydraulic pressure hose 41 exerting pressure between the pressure beam and the individual cylinder-engaging pressure-applying units, so that with any degree of deflection of the beam the individual pressure-applying units exert uni-

form pressure upon the cylindrical tubular roll member 14.

The operation of the invention in several of its various uses is illustrated diagrammatically in Figs. 11 to 18, Figs. 11 and 12 illustrating, for the sake of comparison, a pair of press rolls of heretofore known type. As shown in Figs. 11 and 12, both the upper press roll 14* and the lower press roll 10 are crowned, and in their operative position as shown in Fig. 12 the lower press roll deflects downwardly between its ends supported in the journal bearings 12 and the upper press roll deflects upwardly through the opposed upward pressure upon its intermediate portion and the downward pressures upon its ends produced through the supporting and pressure-applying lever arms 20. In this operative position, the surfaces of the rolls at the nip, where the felt and the paper sheet are engaged, are in substantially straight lines equally spaced and parallel to each other. During rotation of the rolls they continuously flex, and due to their relatively larger diameters at the centers they have greater surface speed at their centers than at their ends. This condition, and irregularities due to faulty crowning, results in the operative disadvantages hereinbefore mentioned, causing non-uniformity in water removal, non-uniformity in paper thickness and surface formation, and rapid deterioration of the rolls and the felt, requiring frequent reconditioning and renewal.

As shown in Figs. 13 and 14, the upper press roll is constructed according to the invention and cooperates with a crowned lower roll 10. In both the static and the operative positions the cylindrical tubular upper roll 14 is straight and uncrowned, so that if the bottom roll is properly crowned to produce a straight line at the nip, there is provided a uniform spacing between the rolls and uniform pressure along the lengths of the rolls. The deflection produced through upward pressure at the center and downward pressure at the ends takes place entirely within the beam 17, and the varying spacing of the beam from the roll surface is compensated for by the pressure-applying units interposed between the beam and the cylinder, the hydraulic pressure applied to these units compensating for variation in the spacing of the beam and producing uniform pressure along the length of the roll.

As shown in Figs. 15 and 16, the roll according to the invention is provided as a bottom roll 14 and cooperates with a crowned top-press roll 14*, the arrangement being substantially the reverse of that shown in Figs. 13 and 14.

In Figs. 17 and 18, both the upper and lower rolls 14—14 are constructed in accordance with the invention. In the operative position the beam 17 of the upper roll deflects upwardly and the beam 17 of the lower roll deflects downwardly.

I have illustrated and described preferred and satisfactory embodiments of the invention, but it will be understood that changes may be made therein, within the spirit and scope thereof, as defined in the appended claims.

Having thus described my invention, what I claim and desire to secure by Letters Patent is:

1. In a press roll structure for use in paper making, a rotatable roll member having a longitudinal space extending therethrough, a longitudinal deflection beam member non-rotatably supportable contiguous to its ends and having its deflection span engaged within said space for relative deflection movement therein, and where-

by a deflection gap is produced between said roll member and the deflection span of said beam member, and a series of yieldable pressure-applying means arranged in longitudinally spaced relation between the ends of said roll member and interposed in the deflection gap between said beam member and said roll member.

2. In a press roll structure, a rotatable roll member having a longitudinal space extending therethrough, a longitudinal deflection beam member non-rotatably supportable contiguous to its ends and having its deflection span engaged within said space for relative deflection movement therein, and whereby a deflection gap is produced between said roll member and the deflection span of said beam member, roll support means arranged internally of said roll member upon which said roll member is rotatably supported, and yieldable pressure-applying means interposed in the deflection gap between said beam member and said roll support means.

3. In a press roll structure, a rotatable roll member having a longitudinal space extending therethrough, a longitudinal deflection beam member non-rotatably supportable contiguous to its ends and having its deflection span engaged within said space for relative deflection movement therein, and whereby a deflection gap is produced between said roll member and the deflection span of said beam member, roll support means movably carried upon said deflection beam member for relative movement parallel to the vertical direction of deflection of said beam member between its ends and upon which said roll member is rotatably supported, and yieldable pressure-applying means interposed in the deflection gap between said beam member and said roll support means.

4. In a press roll structure, a rotatable roll member having a longitudinal space extending therethrough, an internal annular track arranged between the ends of said roll member, a longitudinal deflection beam member non-rotatably supportable contiguous to its ends and having its deflection span engaged within said space for relative deflection movement therein, and whereby a deflection gap is produced between said roll member and the deflection span of said beam member, roll support means movably carried upon said deflection beam member for relative movement parallel to the vertical direction of deflection of said beam member between its ends and engaging said annular track to rotatably support said roll member internally, and yieldable pressure-applying means interposed in the deflection gap between said beam member and said roll support means.

5. In a press roll structure for use in paper making, a rotatable roll member having a longitudinal space extending therethrough, a longitudinal deflection beam member non-rotatably supportable contiguous to its ends and having its deflection span engaged within said space for relative deflection movement therein, and whereby a deflection gap is produced between said roll member and the deflection span of said beam member, and hydraulic pressure-applying means interposed in the deflection gap between said beam member and said roll member.

6. In a press roll structure, a rotatable roll member having a longitudinal space extending therethrough, a longitudinal deflection beam member non-rotatably supportable contiguous to its ends and having its deflection span engaged within said space for relative deflection move-

ment therein, and whereby a deflection gap is produced between said roll member and the deflection span of said beam member, a series of longitudinally spaced roll support means arranged internally of said roll member upon which said roll member is rotatably supported; a series of hydraulic pressure-applying means interposed in the deflection gap between said beam member and said respective roll support means, and hydraulic pressure means common to and connected to said series of hydraulic pressure-applying means.

7. In a press roll structure, a rotatable roll member having a longitudinal space extending therethrough, a longitudinal deflection beam member non-rotatably supportable contiguous to its ends and having its deflection span engaged within said space for relative deflection movement therein, and whereby a deflection gap is produced between said roll member and the deflection span of said beam member, and a hydraulic pressure applying hose-member extending longitudinally through said roll member and

interposed in the deflection gap between said beam member and said roll member.

8. In a press roll structure for use in paper making, a rotatable roll member open at each end and having a longitudinal space extending entirely therethrough, a longitudinal deflection beam member disposed in said space entirely out of contact with said roll member and projecting at its ends beyond the open ends of said roll member, supports at each end of said beam member fixing it against rotation, the span of said beam member between said supports adapted to have vertical deflection movement within the entire length of said roll member, and whereby a variable deflection gap is produced between said deflection span and the vertically opposed side of said roll member, and yieldable pressure applying means interposed in said deflection gap, mounted for yielding and pressure applying movement upon said beam member substantially parallel and coincident to its vertical direction of deflection, and rotatably supporting said roll member.

HARRY G. SPECHT.
